INVENTOR.

UNITED STATES PATENT OFFICE.

JOHN F. O'CONNOR, OF CHICAGO, ILLINOIS, ASSIGNOR TO WILLIAM H. MINER, OF CHICAGO, ILLINOIS.

BUFFER-PLATE-SUPPORTING MEANS.

Specification of Letters Patent.

Patented Feb. 16, 1915.

1,128,355.

Application filed February 28, 1914. Serial No. 821,669.

To all whom it may concern:

Be it known that I, JOHN F. O'CONNOR, a citizen of the United States, residing in Chicago, in the county of Cook and State of Illinois, have invented a new and useful Improvement in Buffer-Plate-Supporting Means, of which the following is a specification.

This invention relates to improvements in buffer plate supporting means.

The object of the invention is to provide means more substantial than those hitherto in use for supporting the buffer plates of vestibule passenger cars to the end that the vestibule diaphragms may also be better supported, the arrangement being such that the buffer plate is connected to the side stems of the buffer devices.

Another object of the invention is to provide a connection between the buffer plate and the supporting side stems therefor which may be adjusted to compensate for wear.

The invention furthermore consists in the improvements in the parts and devices and in the novel combinations of the parts and devices herein shown, described or claimed.

In the drawing forming a part of this specification, Figure 1 is a top plan view of the end floor portion of a vestibule passenger car, parts being broken away to indicate the arrangement of the buffering devices. Fig. 2 is a vertical, sectional view of the structure, taken on the line 2-2 of Fig. 1 and Fig. 3 is an enlarged detail, sectional view taken substantially on the line 3-3 of Fig. 1.

In said drawing, 10, 10 denote the center sills of the car, 11 the end sill and 12 a portion of the floor at the vestibule end of the car. As shown, the usual floor plate 13, buffer plate 14 having foot plate 15 secured thereon, are provided and arranged in the usual manner. The main portion of the buffering device is designated generally by the reference A and is operated in the usual manner through main buffer stem 16, the parts referenced A being located between the center sills in the usual manner. Secured to the outer sides of the center sills are side stem brackets 17 in which are slidably mounted the side stems 18, the latter extending through suitable holes in the end sill 11 and aligned holes 19 in the casting 20 secured to the end sills, the holes or recesses

19 being provided with bearing plates 21 to form suitable bearings for the stems 18. The side stems are kept normally in their outermost position by springs 22 which bear upon the side stem brackets 17 and suitable collars 23 on the stems 18. The foregoing described parts are or may be of any well known construction and do not form any part of my invention.

As shown most clearly in Figs. 2 and 3 of the drawing, the buffer plate which is of substantially angular form, has secured thereto near each end, brackets 24, each bracket having a downwardly extended hollow truncated conical member 25. The ends of the stems 18 are provided with correspondingly shaped conical recesses 26 in which the conical portions 25 are seated, as shown. To hold the parts in position and also to provide means for taking up the wear, a bolt 27 and nut 28 are provided for each connection between a side stem and buffer plate, the nuts being adjustable on the bolts and held in adjusted position by means of cotters 29. As will be understood, the wear which occurs between the various parts will be such as to require the connection between the side stem and buffer plate to compensate for vertical and longitudinal adjustment which is provided for by the cone-shaped members 26 and correspondingly shaped sockets in the side stems and bolts and nuts.

From the preceding description it will be seen that the connection which I have provided between the buffer plate carrying the foot plate, and the side stems is of substantial form; the buffer plate is permitted an angular movement relatively to the side stems as necessitated in the operation of the cars; wear between the parts may be taken up from time to time by means of the nuts thereby minimizing sagging and rattling of the parts; and the diaphragm face plate and other parts which are supported by the buffer plate, are more substantially supported than with arrangements hitherto commonly in use.

Although I have herein shown and described what I now consider the preferred embodiment of my improvements, yet it will be understood that various changes and modifications may be made without departing from the spirit of the invention, and all such changes and modifications are conten-

plated as come within the scope of the claims appended hereto.

I claim:—

1. In a car provided with buffing mechanism having side stems, the combination with a buffer plate and means connecting said plate with the ends of said stems, said means permitting vertical and longitudinal adjustment between said stems and said plate, substantially as specified.
2. In a car, the combination with a buffer plate, of buffer side stems, and means for attaching said plate to the stems, said means including a tapered member seated in a correspondingly shaped socket, substantially as specified.
3. In a car, the combination with a buffer plate, of buffer side stems, and means for attaching said plate to the stems, said means including conical members secured to the buffer plate and seated in correspondingly

shaped sockets in the ends of said side stems, substantially as specified.

4. In a car, the combination with a buffer plate, of buffer side stems, and means for attaching said plate to the stems, said means including conical members secured to the buffer plate and seated in correspondingly shaped sockets in the ends of said side stems and bolts extending through said conical members and the side stems and provided with nuts, whereby the parts may be adjusted to compensate for wear, substantially as specified.

Signed at Chicago, Illinois, this 26 day of February 1914, in the presence of two subscribing witnesses.

JOHN F. O'CONNOR
